UNITED STATES PATENT OFFICE.

JOHN M. JOHNSTON, OF SALEM, OHIO.

TROLLEY-HARP.

1,306,669.

Specification of Letters Patent. Patented June 10, 1919.

Application filed January 14, 1919. Serial No. 271,047.

To all whom it may concern:

Be it known that I, JOHN M. JOHNSTON, a citizen of the United States, residing at Salem, in the county of Columbiana and State of Ohio, have invented new and useful Improvements in Trolley-Harps, of which the following is a specification.

This invention has reference to a novel construction of trolley harp and the principal object of the invention is to hingedly connect the wheel carrying part of the harp to the other part so as to permit the trolley to round curves readily without danger of the wheel leaving the wire.

Another object of the invention is to provide spring means for holding the wheel carrying part of the harp in normal position or in a position to properly engage the straight parts of the trolley wire.

The invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a plan view of the invention.

Fig. 2 is a longitudinal section.

Fig. 3 is a transversal section on line 3—3 of Fig. 1.

Fig. 4 is a view of the sliding member of the harp.

In these views, 1 indicates the harp which consists of the forked member, composed of the stationary part 2 and the sliding part 3, and the arms 4, said arms being hinged to the forked member. The stem 5 of the forked member curves downwardly and is provided with a socket to receive the trolley pole. The end of the stem is provided with the L shaped slots 6 which receive lugs on the pole so as to provide a bayonet joint between these parts. As before stated the forked member is composed of the stationary part 2 and the sliding part 3 and to make a proper connection between these parts the stationary member 2 is cut away on a line extending through the longitudinal center of the stem to a point adjacent the junction of the stem with the member, where the cut is passed through the side of

the stem at right angles. The part 3 is provided with a flat face 7 which engages this face formed by the cut away portion and the length of the part carrying said face 7 is less than the length of the cut away part so that the member 3 may have sliding movement on the member 2, the cut away part forming a shoulder 8 on the stem which acts as a stop for the end of the part 3 to limit the rearward movement of the said part 3. It will thus be seen that the forked member is divided on its longitudinal center to provide the parts 2 and 3, each part carrying one of the legs of the fork. The parts are connected together by providing the part 3 with a dove tail groove 9 and forming a dove tail key 10 on the part 2 to engage with said groove.

The arms 4 are hinged to the ends of the legs of the fork by the pins 11, said ends having recesses 12 and the arms the projections 13 fitting in said recesses and being engaged by the pins. The meeting ends of the legs and arms are rounded as shown in Fig. 1 so that said arms may readily swing on the legs.

The arms are held in normal position by means of the spring plates 14, which have their inner ends engaging the straps 15 secured to the inner faces of the legs of the fork and the outer ends provided with the hooks 16 to engage the rounded outer ends of the arms. The outer ends of the spring plates are enlarged and are provided with the slots or openings 17 to permit the passage of the axle 18 of the wheel 19. The ends of this axle are swiveled in openings 20 in the arms. I prefer to secure the wheel 19 to the axle by means of the set screw 21.

The dove tail connection between the members 2 and 3 may be supplied with lubricant through the openings 22. 23 indicates the eye bolt carried by the harp for receiving the rope.

It will thus be seen that the arms carrying the wheel will swing to one side or the other when the car is passing around the curve thereby lessening the danger of the wheel jumping off the wire. As this swinging takes place the member 3 will slide on the member 2 to keep the arms in parallel positions.

It is thought from the foregoing description that the advantages and novel features of my invention will be readily apparent.

I desire it to be understood that I may

make changes in the construction and in the combination and arrangement of the several parts, provided that such changes fall within the scope of the appended claims.

5 I claim as my invention:—

1. A trolley harp comprising a fork member consisting of a stationary part and a sliding part, arms hinged to said forked member and supporting the wheel and spring means for holding the arms in normal position.
2. A trolley harp comprising a fork member consisting of a stationary part and a sliding part, arms hinged to the ends of the legs of the fork, spring plates having their inner ends connected with said legs and the

outer ends engaging the outer ends of the arms and a trolley wheel having its axle journal in the outer ends of said arms.

3. A trolley harp comprising a fork member 20 consisting of a stationary part and a sliding part, a dove tail connection between said parts, arms hinged to the ends of the legs of the fork, spring plates having their inner ends connected with said legs and 25 their outer ends hooked and engaging the outer ends of the arms and the trolley wheel having its axle engaging said arms.

In testimony whereof I have affixed my signature.

JOHN M. JOHNSTON.
